MOBILE CARRIER

William H. Frick, Cleveland, Ohio

Application October 21, 1955, Serial No. 38,500

Term of patent 14 years

(Cl. D14—3)

Fig. 1

Fig. 4

Fig. 6

Fig. 2

Fig. 5

Fig. 3

Fig. 8

Fig. 1 is a side elevational view of a mobile carrier showing my new design;

Fig. 2 a view in end elevation with one side panel in a folded down position and the top closed,

Fig. 3 a top plan view with both side panels and the top in closed positions,

Fig. 4 a view in side elevation with one side panel in a folded down position and one side of the top in an open position,

Fig. 5 a top plan view with the side panels in a closed position and one side of the top in an open position,

Fig. 6 a view in side elevation with one side panel in a folded down position and slid to an elevated position and one side of the top open, and

Fig. 7 is a horizontal sectional view on the line 7-7 of Fig. 2, and

Fig. 8 is a perspective view, a portion of the view being broken away for better illustration, showing my new design.

I claim:

The ornamental design for a mobile carrier, as shown.
